UNITED STATES PATENT OFFICE.

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY.

STEAM BOILER.

Application filed September 19, 1919. Serial No. 324,817.

To all whom it may concern:

Be it known that I, DAVID S. JACOBUS, a citizen of the United States, residing at Jersey City, in the county of Hudson and State 5 of New Jersey, have invented certain new and useful Improvements in Steam Boilers, of which the following is a specification.

My invention relates to a steam boiler, and more particularly to a steam boiler of the 10 water tube type.

Water tube boilers of the type known in the art as the drop-leg construction—i. e., a construction comprising two banks of water tubes spaced apart to form a secondary combustion chamber between the two banks—have heretofore been built. Difficulty, however, has been experienced with boilers of this type because of the tendency for slag to collect on the tubes of the lower bank and 20 thus obstruct the draft passages.

In accordance with my present invention, this difficulty has been overcome, or largely reduced, by the provision of means for increasing the flow area through the first bank 25 of tubes to the secondary combustion chamber.

My invention will best be understood by reference to the accompanying drawing, in which the single figure of the drawing is a 30 longitudinal section, partly in side elevation, of a steam boiler embodying my invention.

Referring now to the drawing, 1 is the front wall and 2 the rear wall of a furnace, the upper portion of the combustion chamber of which is indicated at 3. The water tubes of a steam boiler are located above the combustion chamber and are divided into two groups, the tubes of the upper group 4^a of which are connected at one end to down-take headers 5^a and at the other end to uptake headers 6^a. The lower bank of tubes, which is here illustrated as consisting of two rows, is indicated by the reference numeral 7^a, and the ends of these tubes are 40 connected to the headers 5^a and 6^a, respectively. The lower bank of tubes 7^a, is spaced from the upper bank to form an unobstructed secondary combustion chamber 12^a, which is of sufficient proportions to allow an 45 operator to enter the chamber when the boiler is shut down for cleaning to remove any slag from the tubes which may not have been reached by the tools passed through the access doors, repair the baffles, and perform 50 any other desired work on parts accessible

from said space, the portions of the tubes of the lower bank 7^a, beneath the secondary combustion chamber, being entirely exposed. It is apparent that the entire tubing enclosing the secondary combustion chamber is accessible from said chamber. The furnace walls are provided with an entrance opening 35 of sufficient size to afford an operator bodily access to said space. Access openings 36 closed by doors 36^a are placed at intervals 60 in the furnace wall beneath the uppermost ends of the tubes 7^a. The slag is removed from the tubes 7^a without shutting down the boiler by means of special tools or rods preferably provided with bent ends, which are 65 passed through the access openings 36 and between the tubes of the lower bank, and by turning the tool, the bent end is brought against the tubes, and by reciprocating the tool, the deposit is removed. By employing 70 the right sort of special tools, practically all of the surface of the tubes 7 where the gases pass between them on entering the first pass can be reached and the exterior of the tubes thereby kept clean. The downtake 75 headers 5^a are connected to a steam and water drum 13 by pipes or nipples 14, and the uptake headers 6^a are connected to the steam and water drum by horizontal pipes 15. 85

A superheater, which I have indicated in general by the reference character A, is preferably located above the water tubes and is here shown as comprising two sets of U-tubes 16 and 17, the two arms of the latter 90 tubes being closer together than those of the former and being disposed within the former. The ends of the U-tubes 16 are connected to boxes 18 and 19, while the ends of the tubes 17 are connected to boxes 20 95 and 21.

In accordance with my invention, provision is made for increasing the flow area through the first bank of tubes to the secondary combustion chamber. 100

The baffle construction B^a comprises two parts, the first part being formed of a baffle 31 disposed above the upper row of water tubes of the lower bank and extending parallel thereto, and the second part of the baffle construction comprising a baffle 32 inclined to the vertical forwardly from the front end of the baffle 31 and extending across the secondary combustion chamber 105 and the upper bank of water tubes to the 110

baffle 26^a, which is disposed between the upper bank of the water tubes and the superheater A. The gases flow from the secondary combustion chamber through the first 5 pass, then over the tubes of the superheater, downwardly through the second pass and upwardly to the third pass, as indicated by the arrows.

In accordance with my invention, the 10 tubes of the lower bank are entirely exposed to the gases and their surfaces are largely exposed to the radiant heat of the furnace, with the consequence that the furnace temperature is lowered, which results in a lesser 15 amount of slag adhering to the tubes.

The space which comes directly above the tubes of the lower bank serves a useful purpose in causing the gases to mingle after they flow over the tubes of the drop-leg and 20 before they enter the spaces between the tubes of the main bank at the bottom of the first pass. Some of the particles of slag will be carried along with the gases in a molten state at the middle part of the spaces between 25 the tubes of the lower bank, whereas the gases which contact with the tubes of the lower bank will be cooled to a point that will cause some of the slag to solidify. By causing the gases to mingle in the space 30 above the tubes of the lower bank before they strike the lowermost tubes of the first pass over the main bank of tubes, the particles of slag will be cooled as a whole and less trouble will result through the adhesion 35 of the slag to the tubes of the main bank than would occur should the tubes of the lower bank be brought in close proximity to the tubes of the main bank.

It will be apparent that, in accordance 40 with my invention, the flow area through the first bank of tubes is greater than that through the first pass of the upper bank, with the consequence that the difficulty arising from the accumulation of slag on the lower bank of tubes has been greatly decreased, and the provision of a construction 45 which enables an operator to enter the secondary combustion chamber and remove any slag that may have formed, further serves to keep the tubes substantially free from 50 deposit. Furthermore, in accordance with my invention, the tubes of the lower bank, beneath the combustion chamber, are entirely exposed to the gases and their surfaces 55 are largely exposed to the radiant heat from the furnace, with the consequence that the furnace temperature is lowered to a point where the brickwork will have a longer life before it is necessary to replace 60 it than it would have in a hotter furnace. This, combined with reducing the obstruction to the flow of the gases on entering the spaces between the tubes, results in a setting 65 that is exceptionally well fitted for the high capacity and high economy under

which boilers must now be operated in certain lines of service.

Inclining the baffle 32 which comes between the first and second passes forwardly, also assists in minimizing difficulties through 70 the dust which collects on the outside of the tubes, this dust being in the main from slag which is cooled to a point by passing between the lowermost tubes that will prevent it from adhering in a fused state. 75 With a vertical baffle between the first and second passes, the dust will collect in solid masses against the baffle at the point where there is still enough heat to allow fused particles to strike the mass and cement it together, and will build out toward the uptake headers. By inclining the baffle as 80 shown, the tendency for the dust to collect against the baffle is reduced and there is a lesser amount of trouble through this action. The arrangement, therefore, provides for a minimum obstruction of the flow of the gases through the boiler in cases where 85 soot and slag is present in the gases.

What I claim and desire to secure by 90 Letters Patent of the United States is:

1. A boiler of the water tube type, comprising a bank of horizontally inclined tubes connected at their ends to water compartments, a steam and water drum above the bank connected to the end compartments, a lower group of tubes comprising a plurality of rows spaced apart from the main bank to give a chamber therebetween, the lower group of tubes being exposed to the furnace chamber beneath for substantially their entire length, a horizontally inclined roof baffle extending from the lower ends of the tubes above the lower group for a portion 95 of the length of the tubes, a transverse baffle extending from the inner portion of said roof baffle forwardly and upwardly at an inclination to the vertical across the tubes 100 of the main bank, the boiler having a down pass at the opposite side of said forwardly inclined transverse baffle.

2. In a steam boiler of the water tube type, two banks of horizontally inclined water tubes spaced apart to form a chamber therebetween of a height equal to a plurality of the rows of tubes, a lower furnace underlying substantially the entire length of the tubes, the lower tubes being exposed to the furnace for substantially their entire length, end water compartments to which the water tubes are connected, an upper drum to which the water compartments are connected, a baffle comprising a roof baffle extending from the lower end of the water tubes intermediate thereof for a portion of their length above the lowermost tubes and having a cross baffle extending upwardly and forwardly from its inner portion at an angle to the vertical, said baffle being arranged to give a down pass to the gases after flowing 110 115 120 125 130

up through the gradually narrowing upward pass.

3. In a steam boiler of the water tube type, two banks of horizontally inclined water tubes spaced apart to form a chamber therebetween of a height equal to a plurality of the rows of tubes, a lower furnace underlying substantially the entire length of the tubes, the lower tubes being exposed to the furnace for substantially their entire length, end water compartments to which the water tubes are connected, an upper drum to which the water compartments are connected, a baffle comprising a roof baffle extending from the lower end of the water tubes intermediate thereof for a portion of their length above the lowermost tubes and having a cross baffle extending upwardly and forwardly from its inner portion at an angle to the vertical, said baffle being arranged to give a down pass to the gases after flowing up through the gradually narrowing pass, the first up pass over the water tubes being at least as large in average area as the second or down pass.

4. A boiler of the water tube type, comprising a bank of horizontally inclined tubes connected at their ends to water compartments, a steam and water drum above the bank connected to the end compartments, a lower group of inclined tubes containing a plurality of rows spaced apart from the main bank to form a chamber therebetween at their upper end portions of a height equal to a plurality of rows of tubes, a furnace having a combustion chamber extending substantially the entire length of the lower exposed rows of tubes, said furnace being of a type which causes slag particles to rise toward the water tubes, a horizontally inclined roof baffle at a level above the lower group of water tubes and extending between water tubes and from their lower end portions for part of their length, and a transverse baffle extending from the inner portion of said roof baffle forwardly and upwardly at an inclination to the vertical and at an inclination to the water compartment facing the same to form a narrowing pass for the rising gases among the upper portions of the water tubes above the chamber, the boiler having a down pass for the gases at the opposite side of said inclined transverse baffle.

5. A boiler of the water tube type, comprising a bank of horizontally inclined tubes connected at their ends to water compartments, a steam and water drum above the bank connected to the end compartments, a lower group of inclined tubes containing a plurality of rows spaced apart from the main bank to form a chamber therebetween at their upper end portions of a height equal to a plurality of rows of tubes, a furnace having a combustion chamber extending substantially the entire length of the lower exposed rows of tubes, said furnace being of a type which causes slag particles to rise toward the water tubes, a horizontally inclined roof baffle at a level above the lower group of water tubes and extending from their lower end portions for part of their length, and a transverse baffle extending from the inner portion of the roof baffle upwardly across water tubes of the upper bank, the upper portions of said cross baffle being nearer the upper ends of such water tubes than are its lower portions to give a narrowing pass for the rising gases among the water tubes above it and to cause the cooler portions of said gases to keep more closely in contact therewith.

DAVID S. JACOBUS.
